Primary Examiner — Sheryl Lane*Assistant Examiner* — Catherine Posthauer(74) Attorney, Agent, or Firm — Davis & Bujold PLLC;
 Michael J. Bujold(57) CLAIM

The ornamental design for a mirror, as shown and described.

DESCRIPTION

FIG. 1 is a perspective view of a mirror, showing my new design from the front, top and right side;

FIG. 2 is a front elevational view thereof; and,

FIG. 3 is a rear elevational view thereof.

Diagonal shading lines indicate that the frame of the mirror is transparent.

The broken lines shown indicate portions of the mirror which form no part of the claimed design.
